UNITED STATES PATENT OFFICE

2,139,623

PRECAST HOLLOW SLAB CONCRETE CONSTRUCTION SYSTEM

James Edgar Marston, Bralorne, British Columbia, Canada

Application October 13, 1937, Serial No. 168,818

9 Claims. (Cl. 72—1)

This invention relates to a new system of pre-cast hollow slab concrete construction to provide a simpler, cheaper and lighter construction than other methods in general use.

5 My system provides for the use of self-supporting floor, wall, roof and partition panels. All material needed for strengthening and providing support to the panels is built thereinto.

10 Means are provided for bolting one panel to another to insure each panel fitting snugly to the other, and tongues and grooves are provided to prevent any misalignment or spreading, and bolting up the whole assembly becomes a rigid unit.

15 Any type or design of house or structure may be fabricated by the use of my system as it is versatile in its application, and houses and buildings having gables, hip roofs, dormers with valleys, may be as readily constructed as more simple types of buildings.

20 I am aware that several United States patents have been granted for building construction, concrete structures and sectional cement structures, but, after reviewing a number of these patents, 25 I find none of them having the important details that distinguish my invention from them, to provide the economic factors and conveniences of structure and assembly that my invention possesses.

30 It is an important object of my invention to provide an improved re-inforced building unit comprising either a wall, a floor partition or roof panel that has a continuous rib or flange extending around both sides and ends, and intersected by longitudinal ribs intermediate the side ribs to divide the panel into a number of smaller panels of elliptical cross section.

35 It is also an object of my invention to provide a type of construction in which the various units entering thereinto may be assembled together without the use of any pre-constructed framework to hold the units in place while being assembled.

40 It is a further object of my invention to provide means integrally secured upon one or both faces of the panels entering into the construction for securing metal laths upon either face for plastering or stucco finish.

45 It is also an important object of my invention to provide an improved form of weather and water strips in the wall and roof panels.

50 It is a still further object of my invention to provide an improved form of roof panel having open re-inforced ribs upon the underside and means at the lower end of the panel to transfer

the roof load directly upon top of the side walls, thereby relieving all over-hang of the roof from strain and stress.

With these and other objects in view, I have invented the system of construction described in the following specification and illustrated in the accompanying drawings forming part of this application, and in which:

Figure 1 is a perspective elevation of part of a building illustrating the use, place and assembly of the various units used in my method 10 of construction.

Figure 2 is a detail and cross sectional view of under side of one of the roof slabs.

Figures 2a and 2b are respectively elevations 15 of the opposite end portions of the slab shown in Fig. 2.

Figure 3 is an elevational detail view of building construction illustrating assembly of floor, wall and roof panels and method of fastening 20 the same.

Figure 4 is a separate detail view of head of bearing partition supporting the jointure of floor panels.

Figure 5 is a transverse and cross sectional view of ground floor panel and illustrates the 25 manner of bolting to another panel.

Figure 6 is a view of open partition panel and shows mounting of set screws.

Figure 7 is a cross sectional view of corner 30 and main partition anchor.

Figure 8 is a side elevation of Figure 7.

Figure 9 is a plan view and end and side views of a main wall panel.

Figure 10 is a cross sectional view of main 35 walls of a building illustrating the elliptical recesses formed in the panels and method of joining and bolting them together and anchoring of a partition to the main wall.

Figure 11 is a detail view of part of a roof 40 having a dormer built thereonto.

Figure 12 is a section of valley of dormer on line 12—12 of Figure 11 showing joining of roof panels at this point.

Figure 13 is a cross sectional view of joint of 45 roof panels showing method of providing a water tight joint by means of a metal feather clamped between joints.

Figure 14 illustrates the manner of lengthening roof panels by bolting of an extension thereto. 50

Figure 15 illustrates one type of metal lath fastener for securing of metal lath thereupon.

Figure 16 is a detail view of metal lath fastener embedded in wall.

In these drawings like numerals indicate like 55

parts and the numeral 1 indicates part of a concrete basement wall or foundation of a building which is provided with a ledge 2 upon the inner face adjacent the top and has a groove 3 formed in the top for the reception of a tongue 4 of a concrete wall panel 5.

Such a wall panel is illustrated in Figure 9 and shows the tongue 4 formed upon the top and bottom edge and one side while a groove 3 is formed 10 upon the opposite side edge.

For the purpose of providing a light, strong wall panel, the latter are formed with a number of elliptical shaped sections 6 enclosed within a continuous surrounding rib 7 and intersected by 15 longitudinal ribs 8 formed between the elliptical sections and the surrounding rib. (See Figure 10).

The ledge 2 is arranged to receive one end of a reinforced floor panel 42 which also has a 20 number of elliptical sections formed therein for lightness and strength, after the manner described for the wall panels.

The reinforcement of these floor panels and likewise the roof panels is preferably an integral 25 iron framework comprising channel irons 9 for the sides and ends and an I beam 10 for the center which are all welded or riveted together to form a rigid framework.

One end of the floor panels is bolted to anchors 30 11 suitably spaced apart and set in the concrete foundation wall above the ledge 2. The inner end of the floor panels upon the under side are provided with a recess 12 which, with the recess formed in the adjacent and joining floor panel, 35 forms a groove in which a tongue 4, formed upon top of the supporting partition or beam 13, registers and provides stiffness and rigidity after the floor panels are bolted together.

The floor panels 42 may be provided with a 40 number of furring grooves 14 for the reception of furring strips upon which a wooden floor may be nailed if desired. (See Figure 5).

Floor panels that are used for second stories are preferably provided with a moulded outer end 45 15, the top of which forms a water table 16 and the lower edge a moulding 17 that overlaps the top outer edge of the wall panels and hides the joint. (See Figure 1).

The top and under side of second story floor 50 panels 18 are provided with grooves for the reception of the tongues 4 of wall panels.

In the center of some of the elliptical sections of the wall panels are provided bolt holes 19 through which bolts are inserted for securing all 55 20 of the members together. Likewise bolt holes are provided through the outer ribs of the panels for bolting of wall and floor panels together. (See Figures 5 and 10).

Ceiling panels 21 may be formed with either 60 open or closed sections between the ribs 7 and 8 of the panels.

In case the upper part of the structure is to be used for an attic with rooms, then the panels would be formed with the usual elliptical sections 65 6 to comprise a floor thereto, but, if no rooms were desired in the attic, then the panels would be formed with open ribs on the lower face of which would be secured metal lath fasteners, after the style of those illustrated in Figure 15, upon which 70 metal lath would be secured for plastering to comprise the ceiling.

All ceiling panels 21 are provided with an outer extension 22 which projects beyond the outer walls of the building to provide the eaves of the 75 roof of the building.

The ceiling panels are provided, on the lower side, with the groove 3 to register with the tongue 4 of the wall panels.

Upon the upper side of the extension 22 there is provided a recess 23 for the reception of a wide 5 tongue 24 formed upon the lower and horizontal base 25 of the roof panels 26 which are also formed with elliptical sections 6 upon the inner or lower face of the panels.

The roof panels 26 are illustrated in Figure 1 10 and separately in Figure 2, which show the latter as having reinforced sides and ends and center.

At the inner end of the horizontal base 25 is formed a vertical face 27 upon which are mounted 15 projecting flanges 28 the upper end of which are rigidly secured to the faces of the iron reinforcements enclosed within the concrete forming the roof panels.

These flanges 28 are secured by the bolts 29 to 20 the top of the ceiling panel which is likewise secured to the wall panel by the same bolt passing through the latter into one of the elliptic sections of the wall panel. (See Figure 3).

For securing the corners of a building together 25 and the intersection of partition walls with the outer walls, I prefer to use anchors 44 such as are illustrated in Figures 7 and 8 and having pockets 30 formed in one end for the reception 30 of the head 31 of securing bolts 45.

By the use of this type of anchor it permits of the wall panels being formed with flat faces and without projections of any kind, and this is an advantage in the handling, assembling and transporting of the panels.

The intersections of the roof panels are provided with a recess 32, such as is illustrated in Figure 13, and are fitted with a metal feather 43 which is clamped between the faces of the joint by the securing bolts 33 when the latter are 40 tightened up, after which the joint is treated with mastic and filled with concrete, preferably waterproofed.

The roof panels, if designed to be lengthened and joined by other roof panels, have the recesses 45 formed horizontally along the top edges of the panel to correspond with like recesses formed upon the lower edges of the joining panels.

In roofs that are fitted with dormers such as are illustrated in Figure 11, and having a valley 50 34, I provide the intersection of the roof panels with a tongue and groove joint 35 such as are illustrated in cross section in Figure 12. The joint is suitably bonded with mastic to make it watertight.

For dividing a building off into rooms, I provide an open partition panel 46 such as is illustrated in Figure 6, having set screws 36 mounted in the top and lower ends which are provided with cupped ends which screw into the concrete 50 of the floor and ceiling panels and rigidly secure the partition panels in place.

One or both faces of the ribs 7 and 8 of these partition panels may be provided with the metal lath fasteners for the mounting of metal lath 65 thereupon, after which the partitions are plastered. These open partition panels may be made to register with open ceiling panels if desired and to form extensions thereto if necessary.

The ridges of the roof panels are joined together by a curved bolt 37, such as is illustrated in Figure 3, but any other type of suitable fastening may be used if desired. The roof ridge is preferably covered by a pre-cast concrete ridge plate such as illustrated at 38 in Figure 3, after 70

the intersection of panels forming the ridge has had the recess joint 39 treated and waterproofed.

The metal lath fasteners which I prefer to use comprise longitudinal strips 40 in which are 5 formed a number of incisions 41 suitably spaced apart, which incisions may be raised up and bent over openings in the metal lath.

The strips 40 are suitably bedded in the concrete at the time of moulding the panels.

10 Having now described my invention and the nature of same, what I claim and desire to be protected in, by Letters Patent, is:

1. In sectional concrete construction, a concrete slab having a metal frame composed of a 15 marginal frame of channel iron and intermediate parallel bars of I beams, one face of the slab being plane and the other face having semi-elliptical grooves between the parallel I-beam portions.

20 2. In sectional concrete construction, a concrete slab having a metal frame composed of a marginal frame of channel iron and intermediate parallel bars of I beams, one face of the slab being plane and the other face having semi-elliptical grooves between the parallel I-beam 25 portions, said slab having bolt holes through its sides and ends, the side holes being countersunk in the semi-elliptical groove.

25 3. In sectional concrete construction, a concrete slab having a metal frame composed of a 30 marginal frame of channel iron and intermediate parallel bars of I beams, one face of the slab being plane and the other face having semi-elliptical grooves between the parallel I-beam portions, the margins of the slab having longitudinal 35 corner recesses adjacent the plane face beyond the adjacent channel iron marginal frame.

4. In sectional concrete construction, a concrete slab having a metal frame composed of a 40 marginal frame of channel iron and intermediate parallel bars of I beams, one face of the slab being plane and the other face having semi-elliptical grooves between the parallel I-beam portions, the margins of the slab being tongued and 45 grooved whereby one slab may be interlocked with another.

5. In sectional concrete construction, a concrete slab having a metal frame composed of a 50 marginal frame of channel iron and intermediate parallel bars of I beams, one face of the slab being plane and the other face having semi-elliptical grooves between the parallel I-beam portions, the I beams of the frame being completely 55 embedded in the concrete, the limbs only of the channel iron of the marginal frame being embedded in the concrete.

6. In sectional concrete construction, a concrete slab having a metal frame composed of a 60 marginal frame of channel iron and intermediate parallel bars of I beams, one face of the slab being plane and the other face having semi-el-

liptical grooves between the parallel I-beam portions, the margins of the slab having longitudinal corner recesses adjacent the plane face beyond the adjacent channel iron marginal frame, the I beams of the frame being completely embedded in the concrete, the limbs only of the channel iron of the marginal frame being embedded in the concrete, and a second slab of like construction to the first secured to the first by bolts passing through the adjacent bolt holes of the two slabs 10 when placed edge to edge, and a V-shaped metal feather located between the adjacent faces of the channel irons of the two slabs and held to seal the joint upon tightening up the bolts.

7. In sectional concrete construction, a concrete slab having a metal frame composed of a 15 marginal frame of channel iron and intermediate parallel bars of I beams, one face of the slab being plane and the other face having semi-elliptical 20 grooves between the parallel I-beam portions, the margins of the slab having longitudinal corner recesses adjacent the plane face beyond the adjacent channel iron marginal frame, the I 25 beams of the frame being completely embedded in the concrete, the limbs only of the channel iron of the marginal frame being embedded in the concrete, a second slab of like construction to the first secured to the first by bolts passing through the adjacent bolt holes of the two slabs 30 when placed edge to edge, and a V-shaped metal feather located between the adjacent faces of the channel irons of the two slabs and held to seal the joint upon tightening up the bolts, the edge wings of the feather lying in said corner recesses, and a filler in the adjacent recesses of 35 the two slabs, whose exposed face is flush with the plane faces of the slabs.

8. In sectional concrete construction, a concrete slab having a metal frame composed of a 40 marginal frame of channel iron and intermediate parallel bars of I beams, one face of the slab being plane and the other face having semi-elliptical 45 grooves between the parallel I-beam portions, the concrete at one edge of said slab being formed as a triangular section to constitute a base, the bearing face of the base lying at an acute angle to the plane face of the slab to adapt said slab to serve as a roof slab.

9. In sectional concrete construction, a concrete slab having a metal frame composed of a 50 marginal frame of channel iron and intermediate parallel bars of I beams, one face of the slab being plane and the other face having semi-elliptical 55 grooves between the parallel I-beam portions, the concrete at one edge of said slab being formed as a triangular section to constitute a base, the bearing face of the base lying at an acute angle to the plane face of the slab to adapt said slab to serve as a roof slab, said bearing face being provided with a wide tongue.

JAMES EDGAR MARSTON.
